CASING HEAD

Filed April 29, 1930

UNITED STATES PATENT OFFICE

FELIX LUCAS PIVOTO, OF BEAUMONT, TEXAS

CASING HEAD

Application filed April 29, 1930. Serial No. 448,379.

This invention relates to casing heads designed to be used after a well has been drilled and is either flowing or being pumped. After a well has been drilled, it is customary to use a small sized pipe in order to bring the oil to the surface and to reduce the volume of oil so brought. The lower end of this pipe or tubing is set on the upper end of the strainer that has been previously set in the bottom of the well in the oil sand, and the upper end of the tubing is brought up to the derrick floor and connected either to what is known as a "Christmas tree" in the case of a flowing well or connected to the stuffing box of a pumping unit. In making these connections, a short piece of pipe known as a "space nipple" is used and the length of this nipple cannot be determined until the tubing has been set and the strain taken out of the tubing. Each joint used to make up this string is from twenty to twenty-five feet long and the whole string may be anywhere from one thousand to five thousand feet long. Under these circumstances, it is a difficult matter to make the pipe come to the exact height to suit the connections without cutting off or adding to the pipe.

One of the objects of this present invention is to provide a body adapted to be connected to the casing of the well and provide an adjustable nipple adapted to be engaged at its lower end with the pipe in the well which extends up through this body, this nipple being adjustable up or down by means of a nut bearing against the body so that by adjusting the nut on the space nipple, slack in the tubing can be let out or taken in as desired or the tubing can be raised or lowered.

A further object is to provide an adjusting nut forming a seal, which adjusting nut is secured upon the nipple so that any oil or gas that may escape around the side of the tubing through a faulty seat on top of the screen, for instance, will be sealed off and forced out

through the connection on the side of the casing head body.

A further object is to provide means for preventing any escape of oil or gas around the threads on the nipple and to this end disposing a stuffing box and gland screwable on to the nipple and fitting into the top of the cover or adjusting nut. 50

A further object is to provide means whereby the well may be sealed instantly as in the case of strong gas pressure where a quick seal may be required in order to lessen the danger of a blow-out where a strong gas pressure is experienced. 55

A further object is to provide means whereby a tubing slip bowl can be fitted in the top of the casing head and tubing slips of any desired kind may be used. 60

Other objects will appear in the course of the following description. 65

My invention is illustrated in the accompanying drawing, wherein:

Figure 1 is a longitudinal sectional view through a casing head constructed in accordance with my invention; 70

Figure 2 is a top plan view thereof;

Figure 3 is a fragmental cross section showing the slip bowl in place in the upper end of the casing head.

Referring to the accompanying drawing, 75
 10 represents an ordinary casing head or body such as commonly used on oil and gas wells having a bore extending entirely through the body, the lower end of the body having interior screw-threads 11 and above these screw-threads the bore extending outward and upward as at 12. At the lower end of this upwardly extending portion 12 of the bore, there is a lateral screw-threaded passage 13 and above the upwardly extending portion 12 of the bore the interior of the body is interiorly screw-threaded as at 14 for engagement with the combination casing head cover, adjusting nut and stuffing box designated generally 15. 80
 85
 90

The lower end of the combination cover, adjusting nut and stuffing box 15 is tapered as at 16 to fit within the tapering portion 12 of the bore. Above this taper 16, it is screw-threaded at 17 to engage the screw-threads 14. Above this, there is an outwardly projecting flange 18 and then the casing head cover extends straight upward as at 19 and has a uniform external diameter somewhat larger than the internal diameter of the lower portion of the bore.

The lower portion of the bore below the flange 18 is interiorly screw-threaded as at 20. Between the screw-threaded portion 12 and the portion 19 having a uniform diameter, there is an inclined packing seat 21.

Adapted to coact with the casing head cover and head cover and adjusting nut 15, there is a stuffing box gland designated generally 22. The lower portion of this gland is reduced in diameter so as to fit within the portion 19 of the casing head cover and at its lower end it is provided with the packing seat 23. The interior of the stuffing box gland is screw-threaded as at 24 and has a diameter equal to the diameter of the screw-threaded portion 20 of the element 15.

Coacting with the screw-threads 20 and 24 is an adjustable space nipple or tubing body designated generally 25. The upper end of the nipple is threaded as at 26 for the stuffing box of the usual polish rod or for the "Christmas tree" and the lower end at 27 is threaded for connection with the tubing of the well. Below the screw-threads 26 there is an unscrew-threaded or blank portion 28 and below this blank portion 28 the nipple is screw-threaded as at 29 to fit the threads 20 of the casing head and the threads 24 of the stuffing box gland. The unscrew-threaded portion 28 of the nipple is designed for engagement by the usual elevators and tongs.

Adapted to be used in connection with the casing head is the tubing slip bowl shown in Figure 2 and designated 30. This has a relatively wide flange 31 and below this flange the slip bowl is somewhat tapered and exteriorly screw-threaded at 32 to fit the screw-threads 14. The interior of the slip bowl is downwardly and centrally tapered. This slip bowl furnishes a table or rest for the tubing slips and is adapted to be used with any ordinary tubing slips.

The slip bowl is preferably formed in two sections as illustrated in Figure 2, these sections being hingedly connected to each other by the plates 33 and the pintles 34. When the stuffing box gland is to be used, packing 35 is disposed between the seats 21 and 23 so as to force down tightly and inward against the screw-threads 29 of the nipple 25.

It will be seen that this casing head is extremely simple and has but few parts. It can be used as a packing head by threading

the lower end of the casing head body exteriorly to engage a surface casing or it can be used in connection with the ordinary packing head by utilizing the threads 11 for engagement with whatever sized liner is used to set the screen. The upper end of the casing head 10 is so formed that in pulling tubing the tubular slip bowl 30 can be fitted in the upper end of the casing head 10 and tubing slips of any kind used. No other casing head has this feature whereby ordinary slips may be used as in all other casing heads known to me specially designed slips must be used. The combination cover, adjusting nut and stuffing box 15 constitutes a positive seal which can be made instantly as in the case of strong gas pressure where the seal is desired quickly. By turning the adjusting nut two or three turns, the seal is made. Furthermore by rotating this element 15 in one direction or the other, the nipple 25 may be raised or lowered, thus eliminating the necessity of taking accurate measurements and cutting a short nipple for making the top connection. It also lessens the danger of a blow-out where strong gas pressure is experienced, while taking measurements and waiting for a short space nipple to be cut to part desired. The upper end of the cover, as previously stated is bored out to form a stuffing box so that the packing 35 may be used to seal off any possible leakage past the threads of the nipple.

It will be understood that the lower end of the casing head 10 is connected to whatever sized casing has been set in the well. The tubing comes up through this casing from the bottom of the well to or through the casing head body 10 and is connected to the nipple 25. The casing head cover and adjusting nut 15 screws on the adjusting space nipple and by adjusting this nut up or down on the space nipple, slack in the tubing can be let out or taken up as desired or the tubing can be raised or lowered. When all of the desired slack has been taken out of the tubing, the cover or adjusting nut is then screwed into the top of the casing head body and forms a seal so that any oil or gas that may be escaping around the side of the tubing through a faulty seat on top of the screen, will be sealed off and forced out through the connection 13 on the side of the casing head. The stuffing box gland 23 prevents any leakage whatsoever through the casing head.

I claim:

1. A casing head comprising a casing head body threaded at its lower end and at its upper end, an exteriorly threaded nipple passing entirely through the casing head body and less in diameter than the interior diameter of the casing head body, a casing head cover and nut having threaded engagement with the upper end of the body and interiorly threaded for engagement with the nipple, the

nut having an upwardly extending annular portion greater in interior diameter than the exterior diameter of the nipple, a gland having threaded engagement with the nipple and bearing upon the upper end of the annular portion of the nut and having a portion extending downward into the annular portion, and packing disposed between the lower end of the gland and the upper end of the screw-threaded portion of the nut.

2. A casing head comprising a casing head body threaded at its lower end and above the threaded lower end extending upward and outward, and then expanded in interior diameter, this expanded portion being interiorly screw-threaded, an exteriorly threaded nipple passing entirely through the casing head and body and less in diameter than the internal diameter of any portion of the casing head body, and a nut having threaded engagement with the nipple, the nut having a flange at its upper end adapted to bear against the upper end of the casing head body below said flange having an exteriorly downwardly tapered threaded portion terminating in a shoulder and below this shoulder being downwardly tapered to fit the surface of the upwardly flaring portion of the casing head body.

3. A casing head comprising a casing head body threaded at its lower end and above the threaded lower end extending upward and outward, and then expanded in interior diameter, this expanded portion being interiorly screw-threaded, an interiorly threaded nipple passing entirely through the casing head and body and less in diameter than the internal diameter of any portion of the casing head body, and a nut having threaded engagement with the nipple, the nut having a flange at its upper end adapted to bear against the upper end of the casing head body below said flange having an exteriorly downwardly tapered threaded portion terminating in a shoulder and below this shoulder being downwardly tapered to fit the surface of the upwardly flaring portion of the casing head body, said nut above the flange being formed with an upwardly extending annular portion greater in interior diameter than the exterior diameter of the nipple and adapted to contain packing and an interiorly screw-threaded gland adapted to have threaded engagement with the nipple and bearing against the upper end of the annular portion.

4. A casing head comprising a casing head body, threaded at its lower end and at its upper end, an exteriorly threaded nipple passing entirely through the casing head body and less in diameter than the interior diameter of the casing head body, an interiorly screw-threaded cover and adjusting nut adapted to fit within the casing head and exteriorly threaded to fit the threads of the upper end of the casing head and having a

flange extending over the upper end of the casing head, said nut and cover having an annular portion of uniform diameter extending upward, an interiorly screw-threaded gland fitting within the upwardly extending portion of the nut and cover, said nipple being of uniform diameter and having threaded engagement with the cover and nut and with said gland, the nipple being exteriorly screw-threaded at its upper and lower ends.

In testimony whereof I hereunto affix my signature.

FELIX LUCAS PIVOTO.
